UNITED STATES PATENT OFFICE.

THOMAS L. HOGAN, OF NEW YORK, N. Y., ASSIGNOR TO THE LILY CUP COMPANY, INCORPORATED, OF NEW YORK, N. Y., A CORPORATION OF NEW YORK.

SLEEVE-PROTECTOR.

1,287,691.

Specification of Letters Patent.

Patented Dec. 17, 1918.

Application filed October 23, 1917. Serial No. 198,020.

To all whom it may concern:

Be it known that I, THOMAS L. HOGAN, citizen of the United States, residing at the city and State of New York, have invented 5 certain new and useful Improvements in Sleeve-Protectors; and I do hereby declare the following to be a full, clear, and exact description of the invention, such as will enable others skilled in the art to which it 10 appertains to make and use the same.

My invention relates to sleeve protectors for protecting the forearm portions of the arms and sleeves of bookkeepers, clerks, saleswomen, and other persons employed in 15 occupations where both neatness of appearance and comfort are desirable and where an accumulation of dust on the arms or sleeves is objectionable. With this in mind, my invention aims to provide a sleeve 20 protector of simple construction and one which may be manufactured cheaply and with exceedingly simple tools; also, it aims to provide simple means for adjusting such a protector to arms or wrists of varying sizes, 25 and simple means for maintaining the parts of the protector in the adjustment suited to any particular shape and size of arm or wrist, and for causing the forward end of the protector to flare out instead of cutting 30 into the wrist or arm. Furthermore, my invention aims to equip a sleeve protector with simple and cheaply manufactured reinforcements for its ends, and also to equip the same with an outwardly directed ink- 35 absorbing or blotter portion conveniently disposed for use by the wearer of this protector. So also, my invention aims to provide a sleeve protector of the above mentioned type, in which no expensive tools 40 will be required either for cutting the blank, for manufacturing the reinforcements, for attaching the blotting element, for uniting certain portions of the blank so as to form a tube from the same, or for attaching a tab 45 in suitable location to maintain the protector in its adjusted position. However, the distinctive elements of my invention may be embodied in a considerable variety of types of sleeve protectors, which varieties 50 do not necessarily need to accomplish all of the objects just mentioned, or contain all of the features hereafter disclosed. For example, I am illustrating several embodiments of my invention in the accompanying

drawings and describing the same more 55 fully in the following specification, from all of which further and more detailed objects will be apparent. In the drawings,

Figure 1 is a perspective view of a sleeve protector, the main element of which was 60 formed from a simple rectangular blank, showing this protector when adjusted to fit a given arm and wrist.

Fig. 2 is a plan view showing the protector of Fig. 1 before it was adjusted to its 65 conical form and while flattened for shipment.

Fig. 3 is a bottom view of the flattened protector of Fig. 2, with a portion of the blotter cut away to show the disposition of 70 the projecting tab part.

Fig. 4 is a perspective view of a sleeve protector formed from a blank having only one end at right angles to its longitudinal sides, and having the blotter in a different 75 position from that of Figs. 1 and 3.

Fig. 5 shows the protector of Fig. 4 when flattened, and before both the ends of the main blank are entirely joined to each other.

Fig. 6 is a transverse section taken along 80 the line 6—6 of Fig. 4.

Fig. 7 is an enlarged longitudinal section through the upper edge of the forward or smaller end of the protector of Fig. 1.

For making the sleeve protector of Figs. 85 1, 2 and 3 I employ for the main element a blank consisting of a simple rectangular sheet of paper or the like, and first score this blank along lines parallel and rather close to opposite longitudinal edges of the latter, 90 so as to define narrow edge strips adapted to flex about the scored lines. Next, I fold the blank twice upon itself along lines extending substantially at right angles to the said reinforced edges, spacing these lines so 95 that the original transverse ends of the blank will overlap at some distance from the fold edges 2 and 3, and thus forming the blank into the shape of Fig. 2. I then secure the tip portion 4 to the tip of the blank which 100 this overlaps, as by pasting, and secure a gummed tab 5 to the outside of the protector thus formed. While this tab 5 need not be shipped attached to the protector, it is desirably placed at one of the fold edges (such 105 as the edge 3) near one end of the protector, and is preferably so disposed as to project considerably beyond this adjacent fold edge.

When the protector has been thus constructed, it is ready for convenient storing and shipping in the flattened form of Fig. 2, in which it occupies very little space. For 5 use, the flattened protector is readily expanded into a tube and slipped over the desired arm, after which a triangular portion of the tube is folded back against the outer surface of the tube, as for example along the 10 dotted line 6 of Fig. 2, thus effectively tapering the protector and causing it to conform to the shape of the given forearm as shown in Fig. 1. When the protector has thus been adjusted to the needed shape, the 15 projecting tab 5 is gummed to the adjacent surface portion of the main tube, as shown in Fig. 1, thereby permanently maintaining the protector in the form of a tube of the desired taper.

20 Where the appliance of my invention is to be used by bookkeepers and others engaged in clerical work involving the use of ink, I desirably also equip the protector with an ink-absorbing or blotting element 7. For 25 the construction of Fig. 1, the blotter 7 may be pasted upon the outer surface of the flattened tube at one end of the latter, and may desirably overlap a portion of the gummed label 5 so as to coöperate with the adhesive 30 on the latter in maintaining the label fast upon the portion of the protector which afterward forms the triangular fold.

It will be obvious from the above description and from the drawings referred to, that 35 only the simplest forms of shears will be required for cutting the blanks for all parts, and that no complicated or expensive tools will be required for any of the forming, 40 scoring or assembling operations. Consequently, I am able to manufacture the sleeve protector of my invention so cheaply as to warrant its widespread adoption for the sales clerks of retail stores as well as for 45 clerical help, and also to warrant its free distribution as an advertising novelty when suitably imprinted with some advertising legend, as indicated also in the drawings. Moreover, by scoring certain parts as above 50 described, I automatically secure the flared front end which enables such protectors,

even if made of thin material, to be worn with comfort.

However, I do not wish to be limited to the use of a blank in which both ends of the proposed tube are cut along straight lines at 55 right angles to the axis of the flattened tube, nor to the particular location of the overlap 4, or the blotter 7 as described, nor to other details of the construction and arrangement here described, except as limited by the appended claims. For example, Fig. 5 shows 60 a protector in its flattened form, having one end cut square, and the other end oblique, thus affording the curvature at the larger end of the protector when in use, as shown 65 in Fig. 4. Likewise, Fig. 5 shows the overlap 4 as disposed close to the fold edge at which the gummed label is attached, shows this gummed tab as partly interposed between the overlapping portions of the main 70 element of the protector, and shows the blotter so located that its greater portion will not be on the part of the protector from which the tapering fold is made.

I claim as my invention:

75 1. A sleeve protector comprising a substantially cylindrical tube of sheet material about to have a portion thereof folded along side the tube to effectively taper the latter, and a projecting gummed tab carried by the 80 portion of the tube which is adapted to form the edge of the fold; the said tab being adapted to be secured to a portion of the tube not overlapped by the fold, so as to hold the latter in its effective position.

85 2. A sleeve protector comprising a substantially cylindrical tube of sheet material adapted to have a portion thereof folded along side the tube to effectively taper the latter, a projecting gummed tab carried by the 90 portion of the tube which is adapted to form the edge of the fold, and a blotter fast upon the tube and lapped over a portion of the tab; the said tab being adapted to be secured to a portion of the tube not overlapped by the fold, so as to hold the latter in its effective position.

95 Signed at Chicago, October 20th, 1917.

THOMAS L. HOGAN.
